INVENTOR:
H. E. BULLOCK,
BY Michael J. Stark & Son
ATTORNEYS.

UNITED STATES PATENT OFFICE.

HENRY E. BULLOCK, OF CHICAGO, ILLINOIS, ASSIGNOR TO ILLINOIS MALLEABLE IRON COMPANY, OF CHICAGO, ILLINOIS, A CORPORATION OF ILLINOIS.

BRAKE-SHOE.

1,160,971.

Specification of Letters Patent.

Patented Nov. 16, 1915.

Application filed July 22, 1915. Serial No. 41,303.

To all whom it may concern:

Be it known that I, HENRY E. BULLOCK, a subject of the King of Great Britain, and resident of Chicago, in the county of Cook and State of Illinois, have invented certain new and useful Improvements in Brake-Shoes; and I do hereby declare that the following description of my invention, taken in connection with the accompanying sheet 10 of drawings, forms a full, clear, and exact specification, which will enable others skilled in the art to which my said invention appertains to make and use the same.

This invention has general reference to 15 brake shoes; and it is especially directed to improvements therein whereby a more serviceable and efficient brake shoe is produced without increasing the cost thereof.

My invention, therefore, consists, essentially, in the novel and peculiar construction and arrangement of parts as herein-after first fully set forth and described, and then pointed out in the claims.

In the drawings already referred to, which 25 illustrate the preferred embodiment, as well as modifications of, my invention, Figure 1 is a side elevation of my improved brake shoe. Fig. 2 is a similar view of a brake-shoe reinforced at the flank thereof, a portion being broken away to show a sectional view of the same. Fig. 3, is an inverted plan of said brake shoe. Fig. 4 is a similar view showing the grooves, recesses or passages therethrough arranged obliquely, or 35 at an angle to the flanks of the shoe. Fig. 5 is a similar view showing the shoe provided with reinforcing plates at the flanks thereof. Fig. 6 is an inverted plan of a shoe showing the grooves, recesses and passages closed at the flanks of the shoe. Fig. 40 7 is a transverse sectional view on line 7—7 of Fig. 1. Fig. 8 is a like view on line 8—8 of Fig. 5, and Fig. 9 is a fragmental view 45 of the shoe illustrating a method of producing the passages, recesses and grooves in the shoe in the process of casting.

Like parts are designated by the same characters and symbols of reference in all the various figures.

It is a well known fact that brake shoes 50 having a continuous wearing face, are liable to glaze, *i. e.* the wearing surfaces become so smooth as to seriously impair their braking efficiency. It is also well known that 55 when the brake shoes are applied to retard

or arrest the movement of a train, they will rapidly heat, thereby causing the shoes to be more quickly worn, without having any noticeable effect on the efficiency of the same. To overcome these defects in, and the objections to, most of the brake shoes now in use, which is the main object of my present invention, I form, in the face or wearing surface 12, of a brake shoe, a series of transversely disposed pockets, recesses or grooves 60 13, the number of which may be varied more or less from those shown in the drawings. These grooves, etc., the contour of which is practically immaterial, serve to break the continuity of the wearing surface, and thereby avoid the glazing thereof. These grooves possess also the property of furnishing a means for the collection of, and affording a ready outlet for, the fine particles of sand, 65 dust, metal, etc., collected from the surrounding atmosphere or caused by the abrading effect of the brake shoes upon the treads of the car wheels; and finally, they serve the purpose of ventilating the brake-shoe by permitting a current or currents of air to 70 pass through the brake shoe and thereby to cool the same. And in order that there be at all times a series of these grooves available as the shoe is worn thinner, I provide the shoe with a series of transverse cavities 75 14, or openings, 14, preferably in rows concentric to the curvature of the wearing surface of the shoe; and to locate these series of rows of apertures so close together that when the grooves 13 begin to disappear 80 owing to the wearing away of the shoe, a new series of such grooves will begin to appear in the face of the shoe, by the opening of the transverse passages 14, so that these 85 grooves continue to be available until the 90 shoe is worn to such an extent as to be of no further use.

As hereinbefore stated, the transverse contour of the grooves 13 and transverse passages or cavities 14 is immaterial; and in 100 Fig. 1, I have shown these grooves in circular, and in Fig. 2, in angular or polygonal contour. And as to the disposition of these grooves and transverse passages, with reference to the flanks of the shoe, I may 105 state that they may be either at right angles to these flanks, as shown in Fig. 3, or at an oblique angle to these flanks, as illustrated in Figs. 4, 5 and 6. While either of these dispositions is effective I prefer the 110

latter or oblique angular position of the grooves for the reason that the scraping action of the shoe on the wheel tread will cause a more ready movement of the fine particles of metallic and earthy matter collected therein, and the discharge therefrom, than right angular grooves afford.

It is obvious that this invention is capable of application in nearly every, if not every, 10 brake shoe now in use or capable of being used, without the slightest change or modification, and I desire it to be distinctly understood that I do not confine myself to any particular design or style of brake shoe, the 15 design shown being simply an exemplification of my invention.

It is also obvious that where in my improved brake shoe the recesses and passages are open at the flanks of the shoe, these 20 passages can be readily produced by the insertion of cores in the mold, which cores are supported by core-prints in the well-known manner. But where these recesses and passages or cavity in the shoe are closed at the 25 flanks of the shoe, the method of producing the cavities is best carried out by connecting these cavities by means of passages starting from the wearing surface of the shoe, and to exemplify one such method, I show in Fig. 30 9 a fragment of a brake shoe wherein 20 designates a core for one of the transverse recesses or grooves in the wearing surface of the shoe. This core has a bridge 21, to connect the core 20 to a core 22, for producing one of the series of cavities 2, and this latter core 22 has a bridge, 23, connecting the core 22 to a further core 24, for producing the next of the series of cavities in the shoe. These cores will support themselves in a 35 mold and may be further supported by the employment of chaplets, in a manner readily understood by persons versed in the art of founding and casting. Of course, other methods of producing the cavities in the 40 body of the shoe may be resorted to, as for instance, the transverse passages in the shoe shown in Fig. 2, may be plugged at the terminals, as shown at 25 in Fig. 6, or these 45 transverse passages in the shoe may be closed by applying to the flanks of the shoe, plates 26, as illustrated in Fig. 8, all of which 50 methods, and others that will readily suggest themselves to persons skilled in the art to which my invention appertains, may be 55 resorted to to effect the object in view of producing cavities in the shoe in the process of casting; and finally, these cavities may be produced in a shoe cast without the same, by drilling the same and plugging the ends 60 of the holes, (or not as the case may be) as heretofore described.

The plates 26 may be secured to the flanks

in any desired manner, as for instance by studs, 27, as shown in Figs. 2, and 8, and thus serve as reinforces to the shoe, to hold 65 the shoe together should it in course of wear, crack, as is frequently the case when the shoe becomes rather thin from wear.

Having thus fully described this invention, I claim as new, and desire to secure to 70 myself by Letters Patent of the United States—

1. As an improved article of manufacture a brake-shoe, there being in the wearing surface of said shoe a series of ventilating grooves and transversely through the body of said shoe and substantially parallel to the wearing face thereof, a series of openings or passages.

2. As an improved article of manufacture, 80 a brake shoe, said brake shoe having in its wearing face a series of ventilating grooves, and transversely through said shoe a series of ventilating passages, said passages being substantially parallel to the 85 wearing face of the shoe, the bottom of said grooves and the lower edge of said passages being in substantial alinement with reference to the wearing face of said shoe.

3. As an improved article of manufacture, 90 a brake shoe, said brake shoe having in its wearing face a series of recesses, and transversely through its body a series of cavities, said cavities being substantially parallel to the wearing face of the shoe, which said 95 cavities are adapted to form recesses when the shoe is worn to an extent to disclose and open the said cavities.

4. As an improved article of manufacture, 100 a brake shoe, said brake shoe having in its wearing surface a series of recesses, and through its body a series of cavities, said recesses and cavities being angularly disposed with reference to the flanks of the shoe, said cavities being substantially parallel to the wearing face of the shoe, said cavities being constructed to afford recesses when the shoe is worn to an extent to disclose and open the said cavities.

5. A brake shoe, said brake shoe having in 110 its wearing face a series of transverse grooves and transversely through the shoe one or more series of apertures, open at the flanks of said shoe, said grooves and said apertures being connected by passages, the 115 lowermost edges of the transverse apertures being slightly below the uppermost edges of said transverse grooves, so that when the said grooves approach disappearance by the wearing of the shoe, the said transverse 120 apertures will begin to show in the wearing face of the shoe and constitute transverse grooves therein.

HENRY E. BULLOCK.
